UNITED STATES PATENT OFFICE

111,517

DESIGN FOR AN ESCUTCHEON PLATE FOR A COMBINED RADIO TUNING DIAL AND CONTROL PANEL, OR THE LIKE

Le Roy J. Leishman, Los Angeles, Calif.

Application October 25, 1937, Serial No. 72,417

Term of patent 7 years

To all whom it may concern:

Be it known that I, Le Roy J. Leishman, a citizen of the United States, residing at Los Angeles, in the county of Los Angeles and State of California, have invented a new, original, and ornamental Design for an Escutcheon Plate for a Combined Radio Tuning Dial and Control Panel, or the like, of which the following is a specification, reference being had to the drawing, forming part thereof.

Fig. 1 is a front elevation of an escutcheon plate for a combined radio tuning dial and control panel, showing my new design.

Fig. 2 is a side elevation on a somewhat enlarged scale.

The characteristic feature of my design consists of the tuning scale opening in association with the station indicating elements and vertical lever slots symmetrically arranged on either side of said opening.

I claim:

The ornamental design for an escutcheon plate for a combined radio tuning dial and control panel, or the like, substantially as shown and described.

LE ROY J. LEISHMAN.
